PHOTOGRAPHIC UNIT

Tom Nerman, Park Ridge, Ill., assignor to Patent
License Corporation, Chicago, Ill., a corpora-
tion of Illinois

Application September 25, 1948, Serial No. 148,764

Term of patent 14 years

(Cl. D61—1)

To all whom it may concern:

Be it known that I, Tom Nerman, a citizen of the United States, residing at Park Ridge, in the county of Cook and State of Illinois, have invented a new, original, and ornamental Design for a Photographic Unit, of which the following is a specification, reference being had to the accompanying drawing, forming a part hereof.

In the drawing:

Fig. 1 is a perspective view of a photographic unit, showing by new design; and

Fig. 2 is a top plan view of the unit as it appears with the camera removed therefrom.

The dominant features of my design reside in the portions shown in solid lines.

I claim:

The ornamental design for a photographic unit, substantially as shown and described.

TOM NERMAN.
